UNITED STATES PATENT OFFICE.

CHARLES F. LANCASTER, OF PETOSKEY, MICHIGAN.

CONCRETE CONSTRUCTION.

No. 920,160.

Specification of Letters Patent.

Patented May 4, 1909.

Application filed May 9, 1908. Serial No. 431,844.

To all whom it may concern:

Be it known that I, CHARLES F. LANCASTER, a citizen of the United States, residing at Petoskey, in the county of Emmet and State of Michigan, have invented certain new and useful Improvements in Concrete Construction, of which the following is a specification.

This invention has for its object a new and useful construction of concrete walls, partitions, sidings, floors, or the like.

As is well known, in concrete work for building purposes, two methods of procedure have heretofore been in vogue. In one of these, the wall, for instance, is built up in courses of ready-made concrete blocks, and this method has its draw-backs or disadvantages in that it is expensive for the reason that the blocks must be handled repeatedly before they are ready to go into the wall, they must be laid up by skilled workmen, and they are laid with soft mortar so that a perfect bed is almost impossible and the joints or union between the blocks are far from perfect, and are not rigid or durable. In the other method heretofore commonly employed, the wall, for example, is built up entirely of soft concrete; but this method has its disadvantages owing to the fact that the molding apparatus is generally expensive and cumbersome, and skilled labor must be employed to do the work, and even then the completed wall is defective on account of the failure of the workmen to properly line up the molds as they are filled in with concrete, it being practically impossible to re-line the work because the concrete sets so quickly after it has been poured into the mold.

It is the primary object of this invention to provide a construction of wall embodying the good features of both of these methods hereinbefore mentioned without their incidental defects, and to this end the invention consists essentially in a wall or other structure built partly of ready-made blocks and partly of "green", or freshly made blocks produced *in situ* the ready-made blocks forming portions of the molds into which

the green concrete is to be poured.

For a full understanding of the invention, reference is to be had to the following description and accompanying drawings, in which:

Figure 1 is an elevation of a portion of a

wall constructed in accordance with my invention. Fig. 2 is a transverse sectional view through another form of wall. Fig. 3 is a horizontal sectional view; Fig. 4 illustrates the invention as applied to tiling; and, Fig. 5 illustrates a modification hereinafter referred to.

Corresponding and like parts are referred to in the following description and indicated in all the views of the drawings by the same reference characters.

In carrying out my invention to produce, for example, a solid wall in contra distinction to the double wall with a dead air space between, I lay upon a suitable foundation or footing, a series of ready-made or set concrete blocks 1 at the desired intervals from each other, and of the required size, shape and facing. Preferably, before these blocks are set, the top surface of the foundation or footing is thoroughly wet and the blocks themselves are thoroughly wet, and dry cement is then sprinkled on the wetted surface and the blocks are slid back and forth to obtain a perfect bed, being finally left in exact position as to line, plumb and space. Mold boards 2 of any desired construction, the more simple, the better, are then clamped onto the ends of the ready-made blocks 1, the surfaces are wetted as are also the ends of the blocks and are then sprinkled with dry cement as before and the space between the ends of every two blocks is then filled in with newly made concrete exactly level with the topsurface of the ready-made blocks 1. Such green concrete is then properly tamped in and becomes as one stone with the ready-made blocks 1, securing a perfect union at the joints. These newly made blocks, produced as above mentioned, are designated 3 in the drawings. After an entire course has thus been formed, the next course is produced and so on until the structure has been completed. Preferably, although not necessarily so, the several courses of ready-made and newly made blocks that are arranged alternately as above described, break joint with each other as clearly illustrated in the drawings.

It is to be understood that my invention is not limited to a single or solid wall. For instance, Fig. 2 illustrates the invention embodied in a double wall with a dead air space between, and in carrying out the method for this specific use, it is clear that the mold may

be clamped to a ready-made block 1^a forming the front portion of the wall at a course so as to serve as supporting means for the mold in producing an accurate alinement 5 and plumb, the newly made blocks 3^a in transverse alinement with the block 1^a. By this method, a dead air space 4 may be formed in the wall. In this particular embodiment of the invention, it is clear that a 10 cheaper grade of concrete may be used for the inner portion of the wall, than for the outer or facing portion.

It is manifest my invention is capable of numerous modifications for the purpose of 15 beautifying a wall or the like by using differently colored concrete for the soft blocks than is used for the ready-made as well as by varying, as desired the design of the blocks and the line of juncture between 20 them. One instance of this is illustrated in Fig. 5, which shows a frieze of which the ready-made sections 5 may be of any desired ornamental design, and the sections 6 and 7 filled in with newly made concrete, or the 25 section 6 may also be formed of ready-made blocks and the section 7 alone of freshly made concrete. By such a structure it is clear that the parts 5 will appear as inlaid work, the cost of which would be relatively 30 very high if produced by any other method than that of my invention.

My invention is also not limited to the construction of walls, partitions, roofs, or sidings, but is also applicable to tile work. An 35 example of this is illustrated in Fig. 4 wherein the blocks 1^b are laid in longitudinal arrangement and secured to the bed in any desired way, the blocks 3^b being subsequently filled in with freshly made concrete 40 in order to complete the tiling, the blocks in this instance, constituting molds.

It is clear that any desired bonding wires (not shown) or reinforcing ties of any construction may be employed with my im- 45 proved method, and that the blocks themselves may be grooved or otherwise formed

to increase the rigidity of the joints of the complete structure.

From the foregoing description, in connection with the accompanying drawings, it 50 will be seen that I have provided a concrete construction, which possesses many advantages from an economic stand point in that the work may be done by unskilled labor, as the ready-made blocks form parts of the mold 55 and properly line up the newly made blocks to the secure and proper alinement, plumb and bed. Furthermore, the molding apparatus may be very simply and cheaply con- 60 structed, and it is easy to understand and easy to handle. Moreover, as it is a well known fact that a wall of this structure should, if possible, be built under cover, or be capable of being quickly covered, in the case of a rain storm, it is clear that my in- 65 vention is possessed of advantages in this respect, for the reason that the ready-made blocks serve as hangers for any covering, whereas without the ready-made blocks, some means independent of the wall must 70 be used as supports for the covers.

Having thus described the invention, what is claimed as new is:

The herein described concrete wall construction comprising newly-made concrete 75 blocks with spaces between of a length co-extensive with the length of the blocks, and blocks produced *in situ* corresponding to the first mentioned blocks and in said spaces, the blocks of one course breaking joint with 80 the blocks of the other course and the newly-made blocks and the ready made blocks alternating, whereby from the bottom to the top of the wall a monolithic structure is produced between the vertically extending 85 newly-made concrete blocks.

In testimony whereof I affix my signature in presence of two witnesses:

CHARLES F. LANCASTER. [L. S.]
